UNITED STATES PATENT OFFICE.

SAMUEL B. WILLIAMS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Original application filed October 23, 1922, Serial No. 596,179. Patent No. 1,517,331, dated December 2, 1924. Divided and this application filed June 21, 1924. Serial No. 721,877.

To all whom it may concern:

Be it known that I, SAMUEL B. WILLIAMS, a citizen of the United States of America, residing at Brooklyn, in the county of Kings and State of New York, have invented certain new and useful Improvements in Telephone-Exchange Systems, of which the following is a full, clear, concise, and exact description.

10 This invention relates to telephone exchange systems and more especially to systems of the class in which automatic switching apparatus is employed for extending automatic connections.

15 In telephone systems where message registration is employed for measuring the service rendered to subscribers' lines, it is frequently necessary to provide for connections to certain classes of lines free of charge.

20 Such lines as these are known as free lines and include lines extended to fire and police stations, hospitals and the like.

25 The object of this invention is, therefore, to enable the extension of calls to certain lines in the system without charge.

30 A feature of the invention relates to a system in which controlling mechanisms serve to govern the operation of selective switches together with means for setting up in such mechanisms a record of the fact that a particular line is being called and means rendered effective according to such record for preventing the call from being charged.

35 Another feature relates to a system having switches comprising a number of links for extending connections to called lines and a special link serving to prevent the charging of a call when the connection is extended to a line of a certain class.

40 This application is a division of the co-pending application of S. B. Williams, Serial No. 596,179, filed October 23, 1922, Patent No. 1,517,331, issued December 2, 1924.

45 Referring to the drawing, Figs. 1, 2 and 3 with Fig. 2 to the right of Fig. 1 and with Fig. 3 below Fig. 1 disclose a sufficient amount of a telephone exchange system embodying the features of this invention to enable an understanding thereof.

50 Fig. 1 discloses schematically a line switch in which subscribers' lines appear together

with one of a number of trunks outgoing from said line switch.

Fig. 2 discloses schematically first and second group selector switches and also a final or connector switch having access to subscribers' lines. This figure also shows diagrammatically connecting devices for associating a marker with the switches.

Fig. 3 at the left diagrammatically illustrates a sender selector switch. Within the left-hand broken area this figure also partially discloses one of a number of common register senders. Within the right-hand broken rectangle there is disclosed a portion of one of a number of markers which serves to control the selective operation of the switches. The figure also shows one of a number of connecting devices for connecting the senders to the markers.

The line switch 101 and selector switches 200, 202, 204 and 300 are of the coordinate type such as disclosed and described in the above mentioned application of S. B. Williams, Serial No. 596,179, filed October 23, 1922, Patent No. 1,517,331, issued Dec. 2, 1924.

The subscribers' lines such as the line 100 appear in vertical rows of contacts in the line switches 101 which have access to trunks such as the trunk 113 leading to the first group selector switches 200. Trunk 113 is seen appearing in the vertical row of contacts in the switch 200 and it will be understood that other trunks similarly appear in the same switch. The selector 200 has access to trunks such as the trunk 201 which appear in vertical rows of contacts of the group selector switches 202. Switches 202 have access to trunks such as the trunk 203 which appear in vertical rows of contacts in connector switches 204.

The particular trunk 203 is seen to appear at the vertical row of contacts 206 in the switch 204. Another trunk incoming from one of the group selectors is seen appearing in the vertical row of contacts 205. The connector switches 204 also have rows of contacts such as rows 207, 208, etc. in which appear subscribers' lines.

The switch 204 has a number of horizontal link circuits which are divided up into a

suitable number of groups or sections 211, 212, etc. The group 211 comprises a number of links 213, 214, etc. for interconnecting the trunks with the lines. Common to these 5 connecting links there is also a special link 215 serving for testing and for other purposes. The section 212 similarly is made up of a number of horizontal connecting links 216, 217, etc. together with a common link 10 link 218.

The subscribers' lines appear in the connector switches in such a manner that they are accessible each to all the links of a given group. For instance, the line 209 is accessible 15 to the links of the group 211. The line 210 is accessible to the links of the group 212. Likewise other lines each appear before all the horizontal links of only one section or group.

20 The register senders 320 are selected by the sender selector switch 300 in response to the initiation of the call and associated with the calling subscriber's line. These register senders comprise in addition to a 25 registering equipment 308, various controlling relays, most of which have been eliminated from this disclosure since they are not needed for an understanding of the invention.

30 The register senders are connectable through devices such as the device 309 with a switch controlling marker, one of which 330 is partially illustrated. The marker 330 contains a registering equipment 310 which 35 receives the record from the registers 308 of the sender and thereby governs the operation of the switches 202 and 204 to extend connection to a called subscriber's line. The manner in which the connection is extended 40 from the line switch 101 through the first group selector switch 200 and also the manner in which the switches 200 and 204 are controlled by the marker 330 to further extend the connection to a called line is fully 45 disclosed and described in the application of S. B. Williams Serial No. 596,179, filed October 23, 1922, Patent No. 1,517,331, issued Dec. 2, 1924.

50 In order to better describe the manner in which the system functions when a call is made to a free line, it will first be assumed that the subscriber of line 100 desires to extend a connection to a line 210, which call, if successful, will involve the operation of 55 the subscriber's message register 102. Thereafter, a description will be made of a call to one of the free lines. Upon the initiation of the call the line 100 is extended through the line switch to the idle trunk 113 leading 60 to the group selector switch 200. The sender selector switch 300 is also operated and the idle sender 320 associated with the calling line. During the operation of the sender selector 300 the relay 103 is operated. Relay 65 103 extends the calling line 100 through to

the impulse relay 302 of the sender, the circuit including the balancing coil 303. Relay 302 operates the holding relay 305 which applies ground potential to the holding conductor 317. The slow release holding relay 70 108 of the trunk circuit is also operated at the time sender selector switch 300 operates and is held in a temporary holding circuit leading through the left front contact of relay 103. Relay 108 applies ground potential 75 to the holding sleeve conductor 115.

After the calling subscriber has recorded the record on the registers 308 of the sender, the switch 200 is operated, whereafter the sender is connected through the device 309 80 with the line marker 330 which proceeds to selectively control the operation of the switches 202 and 204 to establish connection to the called subscriber's line 210.

85 After the connection has been completed and the subscriber's line has been rung, the called subscriber responds, whereupon a circuit is completed for the operation of the supervisory relay 107 in the trunk circuit. This circuit extends through the right windings 90 of the repeating coil 105. At this time the sender has been discharged and relay 103 releases to complete the calling subscriber's line through to the left-hand windings of the repeating coil 105, causing the operation 95 of supervisory relay 106. Relay 106 at its front contact provides a substitute holding circuit for the slow relay 108. When relay 107 operates it causes the operation of relay 100 111 to record the fact that the called subscriber has answered. The circuit for this relay leads from battery through its winding, contact of relay 107, back contact of relay 109, contact 115 to ground at the right contact of relay 108. Relay 111 operates and locks through its winding and right contact, right back contact of relay 112 to ground 105 at the left contact of relay 108.

When the subscribers have finished conversation and replaced their receivers on the 110 switchhooks, relays 106 and 107 release. Relay 106 opens the holding circuit of relay 108, which being slow requires a substantial interval in which to retract its armatures. During this interval a circuit is completed 115 for operating the slow release relay 112. This circuit leads from battery through the winding of relay 112, left contact of relay 111 to ground at the back contact of relay 106. Relay 112 operates and closes a circuit for energizing the magnet 102 of the message register. This circuit leads from ground through the left contact of slow relay 112, conductor 116, through contacts of the line switch 101, winding of the magnet 102 120 to battery. Magnet 102 energizes and operates the register to charge the call.

125 After an interval has expired, relay 112 deenergizes. Thus, a time interval is provided to insure the full and complete opera- 130

tion of the message register 102. The removal of ground potential from the conductor 115 when the subscribers replace their receivers brings about a release of the switches involved in the connection.

It will now be assumed that a connection is desired with the line 209 which is a free line and accordingly no charge should be made against the calling subscriber. In order to place the line 209 on a free line basis, it is only necessary to wire the connecting block 220 in such a way that the conductor 221 which leads to the marker is connected to a contact on the line 209 associated with the common link 215.

The procedure is the same up to the point where the connector switch 204 is being operated. At the time the operating magnet 222 is energized to operate the common horizontal link 215 a circuit is closed for operating the free call relay 312 in the marker to record the fact that the connection being extended is one for which no charge should be made. The circuit for relay 312 may be traced from battery through its winding, conductor 221, connecting block 220, through contacts of the switch 204 in the vertical row 207, thence over the lower conductor of the link 215, thence through contacts of the switch 204 in the vertical row 206, conductor 223 to ground at the contact of the holding relay 311 in the marker. Relay 312 operates and locks through its right contact to the grounded conductor 223. Since the sender is connected to the marker at this time the relay 307 in the sender is operated to record the fact that the connection being extended is one directed to a free line. The circuit for relay 307 leads from battery through its winding, through the connecting device 309, conductor 314, to ground at the left contact of relay 312 in the marker. Relay 307 locks through its right contact to the grounded holding conductor 317.

Later, when the sender is discharged at the completion of the connection through to the free line 209, the relay 109 in the trunk circuit is operated to disable the meter operating means. The circuit for relay 109 may be traced from battery through its winding, right front contact of relay 110, the latter relay being operated at this time, conductor 118, through the sender selector switch 300, conductor 315, front contact of relay 304, left contact of relay 307, contact of relay 306 to ground at the outer right contact of relay 301. The relays 301, 304 and 306 are operated at this time in the manner described in the application of S. B. Williams, Serial No. 596,179, filed October 23, 1922, Patent No. 1,517,331, issued Dec. 2, 1924. The relay 109 of the trunk circuit locks through its front contact to the grounded holding conductor 115.

When the called subscriber answers sub-

sequently, relay 107 operates, but in this case the relay 111 fails to energize since its operating circuit is now broken at the left back contact of relay 109. At the end of conversation when the subscribers replace their receivers, relay 106 releases, but since the relay 111 is deenergized, no circuit is closed for the meter operating relay 112. Accordingly, the connection is released without having operated the calling subscriber's message register 102.

It will be noted in connection with the final switch 204 that an ordinary line may be converted into a free line by merely wiring the connecting block such as the block 220 to make connection with the conductor 221.

In disclosing this invention the drawing has been simplified as far as possible in order to obviate the description of parts of the system which are non-essential to the understanding of said invention. For a full and complete disclosure of a system of the character herein illustrated, reference is made to the above mentioned application of S. B. Williams, Serial No. 596,179, filed October 23, 1922, Patent No. 1,517,331, issued Dec. 2, 1924.

What is claimed is:

1. In a telephone system, a calling line, a register for said line, called subscribers' lines, selective switches for establishing connections between the calling line and said called lines, a controlling mechanism for selectively governing the operation of said switches, means controlled by one of said switches for setting up a record in said mechanism when connections are extended to certain ones of said called lines, means for operating said register, and means controlled by said mechanism when said record is set up therein for disabling the register operating means.

2. In a telephone system, a calling line, a message register for said line, called subscribers' lines, automatic switches for extending connections from the calling line to said called lines, a recording and controlling mechanism common to said switches for selectively governing the operation thereof, means responsive to the operation of said switches for establishing a record in said mechanism when connections are extended to certain ones of said called lines, means for operating said register, and means controlled by said mechanism when said record is established therein for disabling the register operating means.

3. In a telephone system, a calling line, a register for said line, called lines of different classes, selective switches for extending connections from the calling line to said called lines, a controlling device common to said lines and switches, means for associating said device with any switch for governing

- the selective operation thereof, means for establishing a record in said controlling device in response to the extension of connection to a line of a certain class, means for operating said register, and means controlled by said device for rendering the register operating means ineffective.
4. In a telephone system, a calling line, a message register for said line, a called line, selective switches for establishing connections between said lines, a register controlling mechanism for selectively governing the operation of said switches, means for operating said controlling mechanism in a discriminating manner in response to the extension of a connection to said called line, means for operating said message register, means responsive to the called line for preparing to operate said register operating means, and means controlled by said controlling mechanism for disabling said register operating means.
5. In a telephone system, a calling subscriber's line, a register for said line, a selective switch, means for extending the calling line to said switch, other lines outgoing from said switch, said switch having intermediate links for connecting the calling line to one of said outgoing lines, means for operating said register, and a separate link for such switch serving to disable the register operating means when a connection is extended to certain of said outgoing lines.
6. In a telephone system, a calling subscriber's line, a register for said line, a selective switch, means for extending the calling line to said switch, other lines outgoing from said switch, said switch having intermediate links for connecting the calling line to one of said outgoing lines, means rendered effective by the completion of the connection to certain outgoing lines for operating said register, and a separate link for said switch serving to disable the register operating means when a connection is extended to certain of said outgoing lines.
7. In a telephone system, a calling subscriber's line, a register for said line, a selective switch, means for extending a calling line to said switch, other lines outgoing from said switch, said switch having intermediate links for connecting the calling line to one of said outgoing lines, means rendered effective by the completion of the connection to certain outgoing lines for operating said
- register, and a separate link common to all intermediate links serving to disable the register operating means when a connection is extended over certain outgoing lines.
8. In a telephone system, a calling subscriber's line, a register for said line, a selective switch, a register sender for extending the calling line to said switch, other lines outgoing from said switch, said switch having intermediate links for connecting the calling line to one of said outgoing lines, means for operating said register, a separate link for said switch serving to establish a record in said sender when a connection is extended to certain of said outgoing lines, and means controlled by said sender for rendering said register's operating means ineffective.
9. In a telephone system, a calling subscriber's line, a register for said line, called subscribers' lines, a selective switch, means for extending the calling line to said switch, a controlling mechanism for governing the operation of said switch, said switch having intermediate links for connecting the calling line to one of said called lines, a separate link for such switch, means controlled by said separate link for causing the operation of said controlling mechanism when certain ones of said called lines are called, means for operating said register, and means controlled by said mechanism for disabling the register operating means.
10. In a telephone system, a calling line, a message register for said line, called subscribers' lines, selective switches for establishing connections between the calling line and said called lines, a switch controlling marker for selectively governing the operation of said switches, a register sender for recording designations and arranged to cooperate with said marker, means for setting up a record in said marker when connections are extended to certain ones of said called lines, means for controlling the sender in accordance with such record in the marker, means for operating said message register, and means controlled by said sender when said record is set up therein for disabling said message register operating means.

In witness whereof, I hereunto subscribe my name this 9th day of June A. D., 1924.

SAMUEL B. WILLIAMS.
